UNITED STATES PATENT OFFICE.

RALPH E. WILLIAMS AND HENRY H. MORETON, OF LOS ANGELES, CALIFORNIA.

ELECTRICAL CONNECTOR.

Application filed April 8, 1920. Serial No. 372,195.

To all whom it may concern:

Be it known that we, RALPH E. WILLIAMS and HENRY H. MORETON, citizens of the United States, residing at Los Angeles, in the county of Los Angeles, State of California, have invented new and useful Improvements in Electrical Connectors, of which the following is a specification.

This invention relates to an electrical connector and it is an object of the invention to provide an improved device of this character that is simple, effective and inexpensive to manufacture.

A particular object of this invention is to provide an improved simple electrical connector of the general character used in lamps, spotlights, and similar devices. The invention is herein set forth in a form particularly adapted for use in lamps or spot-lights, and the like, but it is not intended that such disclosure should limit or restrict the invention to this particular form or to use in such devices.

An important feature of the invention is the simplicity of construction of the device. The connector provided by the invention is extremely simple in construction and can be easily and inexpensively manufactured. The device requires no complicated or expensive parts, can be easily and cheaply assembled, and is effective and durable.

Further objects and features of the invention are clearly set forth in the following detailed description of a preferred embodiment of the invention throughout which reference is had to the accompanying drawings, in which—

Fig. 1 is a side elevation of a device embodying the invention showing the manner in which it may be used in connection with a removable plug and a lamp; Fig. 2 is an enlarged detailed sectional view of the device shown in Fig. 1; Fig. 3 is a sectional view taken as indicated by line 3—3 on Fig. 2; Fig. 4 is a detailed sectional view taken as indicated by line 4—4 on Fig. 2; and Fig. 5 is an enlarged detail view of the end portion of one of the contacts.

Throughout the drawings numeral 10 designates the electrical connector adapted to make an electrical connection between the removable plug 11 and the bulb 12. This particular combination, that is, the combination of a removable plug and a bulb with the connector 10, is merely to illus-

trate the use of the electrical connector 10, and does not in any way limit or restrict its use to forming a connector between two such devices, as it will be readily understood that it may be used as a connector between various devices and combinations of devices. In the particular form, or embodiment, of the invention illustrated in the drawings the bulb 12 is adapted to be held in, or connected to, the connector 10 in the ordinary manner. That is, a suitable pin 13 is provided on the base 14 of the bulb 12 so as to co-operate with a suitable L-shaped slot 15 formed in the end portion 70 of the casing 16 of electrical connector 10. The plug 11 is adapted to be connected to, or held in engagement with, the electrical connector 10 in a manner common to devices of this general character and in a manner similar to that in which the bulb 12 is connected or held in the electrical connector. Suitable projections 17 are provided in the end portion 18 of the casing 16, and are adapted to co-operate with or engage suitable slots 19 formed in the inner portion of the socket 11. These particular manners of connecting devices to the electrical connector 10 are merely typical and common ways that may be employed and it will be understood that the invention is not in any way limited to such manners of connection but that various other constructions may be advantageously employed.

The electrical connector 10, which is the subject of the present invention, comprises a cylindrical casing 16, a core 20 carried therein, and contacts 21 carried in the core 20. The casing 15 merely provides a carrying member for the core 20 and its ends form sockets in which the plug, and bulb, can be easily and conveniently arranged or held so as to be in engagement with the contacts 21.

The core 20 is preferably a solid or integral block of insulating material such as fibre, or the like, and preferably fits tightly in the casing 15 so that it will not be displaced therein by ordinary use of the device.

There are two independent bores 30 in the core 20 and there is a helical spring 31 carried in each of the bores. It will be noted in the drawings that the springs 31 extend completely through the bores 30 and project from the ends of the core, and that the contacts 21 are carried by the springs. There is a contact 21 at each end of each

2

spring 31 thereby providing two contacts at each end of the core 20 or, two contacts at each end of the connector 10. The contacts 21 are practically uniform in size and shape and each comprises a head or terminal 32 carried on a shank 33. The shanks 33 of the contacts 21 fit within the helical springs 31 so that the ends of the springs engage the inner ends 35 of the terminals 32. The shanks 33 are comparatively long and extend into the core 20. It will be readily understood that the contacts 21 may be attached or connected to the springs 31 in any suitable manner, although, it is preferred that they be attached as follows:

The contacts 21 are held or clamped in vice or clamp jaws, having serrated or irregular faces, during the formation of the terminals 32 thereby causing the shanks of the finished contacts to have serrations or notches 36 near the terminals 32. The helical springs 31 are made to fit the shanks 33 of the contacts 21 rather closely and when the shanks are placed in the springs 31 the contacts are held against dropping off or being easily removed from the springs by the engagement of the serrations or notches 36 by the springs. While the contacts 21 are held in the spring 31 in this manner the terminals 32 and the ends of the springs 31 are dipped into solder, or the like, thereby soldering or securely connecting the ends of the spring to the inner faces 35 of the terminals 32. This manner of connecting the terminals and springs is particularly effective and extremely simple and inexpensive in execution. The contacts 21 may be and preferably are secured to the springs 31 before the springs are placed in the core 20. This is made possible by the terminals 32 being made sufficiently small to be passed through the bores 30. When the contacts 21 have been secured to both ends of the springs 31 the springs carrying the contacts 45 may be inserted in the bores 30 to the proper positions.

A slot 37 is cut a little more than half way through the core 21 to receive a key 38 which locks the springs 31 in place in the core 21 and positively prevents their removal therefrom. The key 38 is preferably a fibre key or a key of insulating material and is made sufficiently large that when the core is placed in the casing 15 it is forced into the slot 37 and pinches or firmly holds the springs against the bottom 39 of slot 37, as clearly shown in Fig. 3. This manner of holding or locking the springs 31 in place in the core 20 is particularly effective, is simple and extremely inexpensive in construction.

It will be particularly noted in the drawings that when the socket 11 is in place in the connector 10 the contacts 40 in the plug 11 are in position to engage the terminals 32, and that when the bulb 12 is in place in the

connector 10 the base 14 is in engagement with the contacts 21. When the contacts are in engagement with the plug and bulb, or when they are depressed the shank 33 of the contacts 21 are comparatively close to or are near the key 38. This construction, or the provision of long shanks 33 on the contacts causes the contacts 21 to be firm, and also makes it necessary for the electricity being carried by the connector 10 to pass through only short lengths of springs 31 thereby making the resistance of the connector 10 practically negligible.

It will be readily understood how the springs 31 cause the terminals 32 of the contacts 21 to be firmly pressed or held against the base 14 of the bulb 12 and the contacts 40 of the plug 11 when the base and plug are in place in the connector 10, as shown in Figs. 1 and 2. The terminals 32 being held against the base 14 and contacts 40 by the springs 31 make good electrical connections with these parts thereby rendering the connector 10 effective and efficient. It will be readily understood how the contacts 21 move out to the position shown in dotted lines in Fig. 2 when the bulb 12 and plug 11 are moved from the connector and how the key 38 positively prevents displacement of the spring in the core 20 when the bulb and plug are removed.

Having set forth a preferred embodiment of the invention we do not wish to limit or restrict ourselves to the particular details above set forth but wish to reserve to ourselves any changes or variations that may appear to those skilled in the art or that may fall within the scope of the following claims.

Having described a preferred form of our invention, we claim:

1. In an electrical connector, an insulating member having a pair of bores extending through it and a slot in it and extending across the bores, two springs each having terminals at their ends arranged in the bores so that their ends project from the insulating member, and a single key of insulating material arranged in the slot to engage and hold both springs.

2. In an electrical connector, an insulating member having a bore extending through it and a slot in it and extending across the bore, a single spring having terminals at its ends carried in the bore, and a key arranged in the slot to engage the spring, and a casing around the insulating member positively preventing displacement of the key.

3. In an electrical connector, an insulating member having a pair of bores extending through it and a slot in it and extending across the bores, two springs each having terminals at their ends arranged in the bores, and a single key of insulating ma-

terial arranged in the slot to engage and hold both springs, and a casing around the insulating member positively preventing displacement of the key and extending from the insulating member to form sockets.

4. In an electrical connector, an insulating member having a pair of bores extending through it and a slot in it and extending across the bores, two helical springs carried in the bores so that their ends extend from the insulating member, a single key arranged in the slot to lock both springs against displacement in the bores, and contacts carried by the ends of the springs, the contacts comprising terminals at which the springs connect to the contacts and shanks which project freely into the springs.

5. In an electrical connector, an insulating member having a pair of bores extending through it and a slot in it at right angles to and across the bores, a helical spring carried in each bore, a single key of insulating material arranged in the slot to extend across the bores and prevent displacement of both springs, a casing around the insulating member positively preventing displacement of the key and projecting from the insulating member to form sockets, and contacts carried at the ends of the springs

to extend into the sockets formed by the 30 casing.

6. In an electrical connector, a cylindrical insulating block having a pair of spaced longitudinal bores and a transverse slot at its middle and extending across the bores, a 35 helical spring in each bore, a single key of insulating material arranged in the slot to extend across the bores and prevent displacement of both springs, a cylindrical casing around the insulating block to prevent 40 displacement of the key and extending from the insulating block to form sockets at its ends, and contacts carried at the ends of the springs to extend into the sockets formed by the casing, the contacts comprising terminals at their outer ends to which the ends of the springs connect and shanks extending freely into the springs and adapted to closely approach the key when the springs are compressed. 45

In witness that we claim the foregoing we have hereunto subscribed our names this 24th day of March, 1920.

HENRY H. MORETON.
RALPH E. WILLIAMS.
